US00D594169S

(12) **United States Design Patent**
Connor et al.

(10) **Patent No.:** US D594,169 S
(45) **Date of Patent:** ** Jun. 9, 2009

(54) **ACCUMULATION BIN**

(75) Inventors: **Pat Connor**, Kitchener (CA); **Paul Goyette**, Penetanguishene (CA); **Gordon Bennett**, Midland (CA)

(73) Assignee: **Jake's Holding Corporation**, Kitchener, Ontario (CA)

(**) Term: **14 Years**

(21) Appl. No.: **29/278,675**

(22) Filed: **Apr. 5, 2007**

(51) **LOC (9) Cl.** 09-09

(52) **U.S. Cl.** D34/5

(58) **Field of Classification Search** D34/1, D34/5, 6, 7, 8, 9, 10, 11; 220/908, 909, 910, 220/810, 811, 812

See application file for complete search history.

CLAIM

The ornamental design for an accumulation bin, as shown and described.

DESCRIPTION

FIG. 1 is a bottom perspective view of an accumulation bin exemplary of an embodiment of the design;

FIG. 2 is a rear perspective view of the accumulation bin of FIG. 1;

FIG. 3 is a left-hand side elevational view of the accumulation bin of FIG. 1;

FIG. 4 is a front elevational view of the accumulation bin of FIG. 1;

FIG. 5 is a right-hand side elevational view of the accumulation bin of FIG. 1;

FIG. 6 is a rear elevational view of the accumulation bin of FIG. 1;

FIG. 7 is a top plan view of the accumulation bin of FIG. 1; and,

FIG. 8 is a bottom plan view of the accumulation bin of FIG. 1.
